UNITED STATES PATENT OFFICE.

JAMES C. RICHARDSON, OF BOSCOBEL, WISCONSIN.

YARN-SCOURING MACHINE.

SPECIFICATION forming part of Letters Patent No. 262,832, dated August 15, 1882.

Application filed November 1, 1881. (Model.)

To all whom it may concern:

Be it known that I, JAMES C. RICHARDSON, a citizen of the United States, residing at Bos-
5 cobel, in the county of Grant and State of Wis-
consin, have invented certain new and useful
Improvements in Yarn-Scouring Machines;
and I do declare the following to be a full, clear,
and exact description of the invention, such as
will enable others skilled in the art to which it
10 appertains to make and use the same, reference
being had to the accompanying drawings, and
to the letters and figures of reference marked
thereon, which form a part of this specification.

My invention relates to a machine adapted
15 especially for scouring or washing yarn, yet
serviceable with efficiency for other purposes;
and the novelty consists in the construction
and arrangement of parts, as will be more fully
hereinafter set forth, and specifically set forth
20 in the claims.

The object of the invention is to provide a
revolving reel or compound expanding roller
which will allow the rolls thereon to be dis-
placed until the several hanks, skeins, or the
25 like of yarn are placed upon the reel or com-
pound expanding roller, and to give to such
rolls such an independent revolution in their
own bearings, operated by the novel mechani-
cal movement shown, as will change the point
30 of bearing upon each of the rolls in the box
with each revolution of the reel, as will be set
forth.

The invention is fully illustrated in the ac-
companying drawings, which form a part of
35 this specification, and in which Figure 1 is an
end elevation, partly in section, of the inter-
nal box, &c., removed from the vat; Fig. 2, a
top plan view with the reel removed; Fig. 3, a
plan view of the reel; and Fig. 4, an end view
40 of the reel, showing the cams.

To enable others skilled in the art to which
the invention relates to make and use the in-
vention, I will describe its construction and
operation, and to this end I refer to the said
45 drawings by letter, similar letters of reference
indicating like parts in each figure.

A represents the tub or receptacle, having
a bearing, *a*, upon one side of the box *A* for
one end of the shaft *A'*, and an angular recess,
50 *a'*, upon the opposite side, adapted to receive
a correspondingly-formed box, *B*, in which is
journaled the other end of the shaft *A'*.

B represents the box, which fits in the re-
cess *a'*, and in which the shaft *A'* is journaled;
B', the roller-heads, having projecting pins
b'; and *b*, the pins projecting from the box *B*.

The box *B* being stationary and the pins *b*
operating in the links of an endless chain, *B*²,
which chain also operates over the pins *b'* in
the roller-heads *B'*, not only is the reel rotated
60 by the direct action of the shaft *A'*, but the
action of the chain, in connection with the
roller-heads *B'* *b'*, serves also to give to each
roll *C* a steady and independent revolution as
the shaft *A'* is rotated.

The rolls *C* are journaled in cross-arms *D*,
slotted at *d*, to which are attached, by proper
set-screws, *e*, head-plates *E*, having segmental
slots *f*, in which the set-screws *e* operate. The
set-screws *e* being loosened, the roll-shafts *C*
70 are allowed to be adjusted upon cam-faces *E'* at
will, to apply the skein or hank, or to adjust the
tension of the same after it has been applied.
Each roller *C* operates in conjunction with
rollers *H*, having shafts *h* journaled in radial
75 slots *i* in a removable internal box, *I*, and each
roll is held centrally by the constant force of
a spring, *x*. The rolls *H* are arranged semi-
circularly or segmentally, and the sections may
80 be arranged so as to form a closed box with a
complete circular system of rollers.

It will be observed that each roller *C* makes
contact with each of the series of rolls *H*, that
the hanks or skeins of yarn or the like are
stretched upon said rolls *C*; and that the rolls
85 *C* revolve arbitrarily with the revolution of the
expanding roll and independently in their own
journals; that the yarn or the like will be so
rotated; and that a different portion of the
yarn will be forced in contact with the spring-
90 rolls *H* until a complete scouring is effected.

Limited modifications in details of construc-
tion may be made without departing from the
principle or sacrificing the advantages of my
invention, the essential features of which con-
95 sist in the spring-rollers *H*, the rollers *C*, head-
plates *E*, having slots *f* and cam-faces *E'*, and
means for imparting a rotating movement to
each roll *C* independently.

What I claim is—

1. In a yarn-scouring machine, a compound
expanding roller composed of a slotted frame,
independent rolls journaled therein, and cam-
faced heads, means for imparting to such in-

dependent rolls a continuous and independent rotary motion, and spring bearing-surfaces, the whole adapted to serve as and for the purposes set forth.

5 2. In a yarn-scouring machine, a reservoir, A, and a contained removable box or frame, I, having spring-rolls arranged semicircularly, segmentally, or circularly, combined with a revolving compound expanding roller, the independent rolls C of which make contact with said spring-rolls, and said rolls C having an independent rotary motion, as and for the purpose set forth.

10 3. In a yarn-scouring machine, means, substantially as described, for contracting the compound expanding roller to allow of the placement of the skeins or banks, and means, substantially as described, for imparting to each independent roll C an independent rotary motion, combined with flexible or spring bearings, arranged as shown, as set forth.

15 4. The independent rolls C, journaled in the frame-arms D d, combined with the endless

chain B, B', B², &c., and arranged to make contact with a series of rolls provided with spring- 25 bearings, substantially as set forth.

5. The removable box or frame I, having sockets i and springs x, the rolls H, arranged in the form of a segment, combined with the reservoir A, and the compound expanding roller, 30 having the independent rolls C, as and for the purposes specified.

6. The head-plate E, slotted at f, and set-screws e, combined with the cam-faces E', the rolls C, rolls H x, and motive power, substantially as and for the purposes set forth. 35

7. In a yarn-scouring machine, the cams E E', combined with the rolls C and frame D d, and adapted to adjust the tension of the yarn upon the rolls C at will, as specified. 40

In testimony whereof I affix my signature in presence of two witnesses.

JAMES C. RICHARDSON.
